F. P. BICKNELL

LABELING DEVICE

Filed April 14, 1924

UNITED STATES PATENT OFFICE.

FRANK P. BICKNELL, OF DENVER, COLORADO.

LABELING DEVICE.

Application filed April 14, 1924. Serial No. 706,418.

To all whom it may concern:

Be it known that I, FRANK P. BICKNELL, a citizen of the United States of America, residing at Denver, in the county of Denver and State of Colorado, have invented certain new and useful Improvements in Labeling Devices, of which the following is a specification.

This invention relates to a device for placing labels upon cans, bottles and the like, and has for its principal object the provision of a device of this character which can be efficiently used in small establishments where the expense of a mechanical machine-operated labeler would be prohibitive or unnecessary.

A further object of the invention is to so construct a labeling device that it will be practically universal in its application to bottles or cans of various shapes and sizes, and to labels of various shapes and sizes.

Other objects and advantages reside in the detail construction of the invention, which result in simplicity, economy and efficiency, and which will become more apparent from the following description.

In the following detailed description of the invention, reference is had to the accompanying drawing which forms a part hereof. Like numerals refer to like parts in all the views of the drawing and throughout the description.

In the drawing:

Fig. 1 is a perspective view of the improved labeling device.

Fig. 2 and Fig. 3 are detail sections through the labeling frame, illustrating the operation thereof.

Fig. 4 and Fig. 5 are detail views of various pasting or moistening rollers which are used in the device.

Fig. 6 is a perspective view of the label frame employed in the device when labeling cylindrical bottles or cans.

Fig. 7 and Fig. 8 are detail views illustrating the operation of placing a label on a cylindrical object.

Broadly, the device comprises a base board 10, upon which is mounted a paste or liquid container 11, a pasting roller 12, two pressing rollers 13, and a label frame 14.

The container 11 is used to contain paste or mucilage, when applying plain labels; and for containing water, when applying gummed labels. The roller 12 projects into

contact with the liquid in the container 11 and transfers the liquid to the object being labeled. In the following description, the liquid used will be referred to as paste. 60

The label frame 14 is flexibly supported above the base board 10 on four coil springs 15, which surround four guide pins 16. The guide pins 16 are securely imbedded in the base board and project into openings 17 in 65 the label frame 14. The openings 17 may be protected from wear by metal ferrules 18, if desired.

The label frame 14 is provided with an opening 19 of the proper size and shape to 70 conform to the contour of the labels being used. Register stops 23 and 24 are secured to the face of the label frame to properly align the bottles or other articles with the label opening 19. 75

A label block 20 is fitted within the opening 19 and rests upon the base board 10, dowel pins, 21, being arranged in the base board to hold the block in alignment within the opening 19. 80

In use, a stack of labels, 22, is placed face downward upon the label block 20, within the opening 19. The bottle, or other object upon which it is desired to place a label, is drawn across the roller 12, bottom first. 85 The roller 12 applies a coat of paste to the face of the bottle. The bottle is rolled from the roller 12 onto the label frame 14 against the register stops 23 and 24 and occupies the position indicated in broken lines at 90 9, Fig. 2.

The bottle is now pressed downward, compressing the springs 15, to the position indicated in Fig. 3. It will be noted that the pasted side of the bottle is now in contact 95 with the back of the upper label of the stack 22, to which, it will adhere. The pressure is now released from the bottle, allowing the springs 15 to force the label frame back to its normal position, and the bottle 100 is passed over the pressing rollers 13 which roll the label securely into place. This operation is continuous until the stack of labels 22 has been exhausted. The pasting roller 12, shown in Fig. 1, is cylindrical and 105 is adapted only for use on flat sided bottles.

When it is desired to use the device for labeling cylindrical bottles or cans, the roller 12 is replaced by a roller 25, illustrated in Fig. 4, and the label frame 14 is replaced by 110 a label frame 26, illustrated in Fig. 6. The roller 25 has three surfaces, 27, 28 and 29,

which contact with the bottle as it is rolled thereon. The contact is illustrated in Fig. 4, in which, the bottle is indicated in broken line at 39. The surfaces 27, 28, and 29, 5 apply three lines of paste to the bottle, indicated at 27', 28', and 29', respectively, Fig. 7.

The bottle is passed from the roller 25 onto the label frame 26, which is provided 10 with blocks 30 conforming to the contour of the bottle, to a position against the register stop 23. The blocks 30 are so positioned that they will come into contact with the bottle between the lines of paste thereon 15 as not to scrape and smear the paste.

The label frame is now depressed bringing the middle line of paste, 29', into contact with the middle of the upper label and causing it to adhere to the bottle as shown 20 in Fig. 8. The bottle is now transferred to the pressing rollers 13 and rotated thereon. This rolls the label into contact with the outer lines of paste, 27' and 28', as illustrated in Fig. 8.

25 When labeling convex or oval bottles, pasting roller 31, illustrated in Fig. 5, is used, which has a contour to conform to the label side of the bottle.

A series of slots 32 are provided for the 30 reception of the pasting rollers and to allow for the adjustment thereof. The slots closest to the label frame are used when labeling short bottles so that the bottom end of the bottle will have passed onto the label frame before the other end leaves the pasting roller. When labeling long bottles, the pasting roller is moved outward in the slots to insure the bottle leaving the pasting roller before the label frame is depressed.

40 In order to prevent the label frame from passing above the label block and allowing the escape of the labels, a flange 34 is formed on the label block 20, which contacts with a flange 35 formed on the interior of the opening 19.

45 Screws 36 hold the register stops 23 and 24 in place and allow them to be adjusted with reference to the label hole 19 so that the label may be placed at any desired position on the bottle.

The flexibility of application of the device can be readily appreciated, since, by 55 simply changing the pasting roller it can be adapted to various contours of bottles and by changing the label frame it can be quickly adapted to various sizes and shapes of labels. These changes can be quickly made since it is only necessary to lift off the roller and frame and replace the others. The 60 pressing rollers 13 need not be changed since

they operate equally well with any shape of bottle.

It is preferred to make the entire device of wood to eliminate breakage of bottles. The rollers are formed with a wooden core 32 65 (Fig. 8) wound with felt or similar material 33.

While a specific form of the invention has been described and illustrated herein, it is desired and understood that the same may 70 be varied within the scope of the appended claims without departing from the spirit of the invention.

Having thus described my invention, what I claim and desire to secure by Letters Pat- 75 ent is:—

1. A labeling device comprising in combination a base; a liquid receptacle mounted on said base; a roller mounted over said receptacle and projecting therewithin; label 80 applying means mounted on said base adjacent said roller and other rollers mounted on said base alongside of said applying means said rollers and said applying means being so arranged that the article being 85 labeled will travel from one to the other without being carried or lifted.

2. A labeling device comprising in combination a base; a pasting roller mounted on said base; a flexibly mounted label-frame 90 mounted on said base adjacent said pasting-roller so that the article being labeled will enter said frame before leaving said pasting-roller, said frame being provided with an opening for the reception of a stack of 95 labels; a block mounted on said base within said opening and a pressing-roller mounted on said base alongside of said label-frame so that said article will enter on said pressing-roller before leaving said label frame. 100

3. In a labeling device, means for applying liquid to the article being labeled comprising, a liquid receptacle and a roller projecting therewithin, said roller having a plurality of surfaces shaped to conform to the 105 contour of said article and arranged to apply parallel lines of liquid to said article.

4. A labeling device comprising a base; pins secured in said base; a label-frame having an opening for the reception of a stack 110 of labels and other openings for the reception of certain of said pins; a block, shaped to slidably fit within said first mentioned opening, said block having openings for the reception of other of said pins, and springs 115 arranged to operate between said base and said label-frame.

In testimony whereof, I affix my signature.

FRANK P. BICKNELL.
